UNITED STATES PATENT OFFICE.

WORTH R. BARRINGER, OF DENVER, COLORADO, ASSIGNOR TO THE SUBMERSIBLE BOAT COMPANY, A CORPORATION OF COLORADO.

SUBMERSIBLE BOAT.

1,278,090.

Specification of Letters Patent. Patented Sept. 10, 1918.

Application filed January 16, 1918. Serial No. 212,056.

To all whom it may concern:

Be it known that I, WORTH R. BARRINGER, a citizen of the United States, residing at Denver, in the county of Denver and State 5 of Colorado, have invented certain new and useful Improvements in Submersible Boats, of which the following is a specification, reference being had to the accompanying drawings.

10 This invention relates to an improved submersible boat, and has for its primary object to provide a vessel of this character which is constructed to contain a single occupant, and is provided with means whereby the 15 submergence of the vessel and its travel through the water may be controlled by the occupant.

It is also an object of the invention to provide a vessel of the above character which is 20 very light in weight and can be conveniently employed in submarine observations, or in the removal of submerged mines, and for various other analogous purposes.

And it is also a secondary though an important object of my invention to provide a vessel of the above character, which is substantially in the nature of a diving suit and can be readily donned by the individual, the device therefore lending itself to use as 30 a life saving apparatus to be carried upon passenger steamers as a part of the equipment thereof.

With the above and other objects in view, the invention consists in the novel features 35 of construction, combination and arrangement of the several parts as will be herein-after more fully described, subsequently claimed and illustrated in the accompanying drawings in which similar reference charac- 40 ters designate corresponding parts throughout the several views and wherein:

Figure 1 is a perspective view illustrating one form or embodiment of my improved submersible boat;

45 Fig. 2 is a longitudinal section thereof;

Fig. 3 is a section taken on the line 3—3 of Fig. 2; and

Fig. 4 is a section taken on the line 4—4 of Fig. 2.

50 Referring in detail to the drawings, 5

designates the body of the boat or vessel which is preferably constructed of aluminum or other light sheet metal and which may be of any approved form and construction. In the accompanying drawings I have 55 shown the body of the vessel having a configuration simulating the form of an aquatic animal, said body having a nose indicated at 6 and provided in opposite sides of said nose portion with the transparent panes or windows, indicated at 7, and in its body portion with a similar transparent pane 8 whereby the operator may obtain a clear view so that he can readily avoid obstructions and properly guide the vessel to the desired anchorage or destination.

To the opposite end of the metal body 5, which is of contracted transversely elongated tubular form, a plate 9 is secured by means of a suitable water tight joint, and 70 this plate carries the tubes or envelopes 10 of rubber or other suitable flexible material to receive the legs of the operator. Upon the bottom wall of the body 5 a longitudinally extending support 11 is suitably secured or constructed, having its upper surface shaped so that the operator may lie thereon without discomfort in the position shown in Fig. 2 of the drawings. In a suitable compartment 12, preferably at the 75 top or upper side of the body 5, an electric motor 13 is arranged and the motor shaft is operatively connected to the propeller shaft 15 by means of the endless chain 14 which extends around suitable guides indicated at 14' secured to the opposite walls of the body 5 of the vessel. The propeller 16 which is fixed upon the shaft 15 may be of any approved form.

If desired, in addition to the electric motor 13, a compressed air motor 17 may be provided, the latter being preferably arranged in the lower portion of the body 5 and operatively connected to the propeller shaft 15. This motor is supplied with 90 compressed air from a storage tank indicated at 18. 20 designates a vent for the vitiated air and 21 air inlets or ventilators arranged in the top wall of the body 5. The vent 20 and ventilators 21 100

are provided with suitable valves, preferably of the floating ball type which will be automatically closed by the pressure of the water upon the submergence of the vessel to prevent the entrance of water to the interior thereof, said valves immediately opening when relieved of such pressure. An electric light bulb 22 is also arranged in the top wall of the body 5 immediately above the nose 6 and may be supplied with current from suitable storage batteries.

To the opposite sides of the body 5 at the proper points sleeves 23 of rubber or other suitable flexible material are securely attached, said sleeves being equipped at their extremities with suitable gloves to receive the hands of the operator. It will of course be understood that the connections of the gloves to the sleeves and of the sleeves to the sides of the vessel body must be absolutely water tight to prevent the entrance of water to the interior of the vessel. Preferably, shoulder straps indicated at 24 are secured within the body 5 and are fastened around the shoulders of the occupant so that the weight of the vessel will be sustained from the shoulders when the occupant is walking or in a standing position.

To the underside of the body 5 rearwardly of the sight glass 8 a collapsible tank 25 is arranged. This tank 25 is equipped at its lower end with suitable valves indicated at 26 and hand holds 27 adjacent to said valves. 28 designates a pipe or conduit connecting the compressed air tank 18 to the upper end of the collapsible tank 25 and in this conduit a suitable valve 29 is located. The valves 26 and 29 may be of any ordinary or approved form.

40 In the operation of the vessel, when it is desired to submerge the same, the tank 25 is collapsed, the air being expelled from the tank through the valves 26. This results in the displacement of the vessel so that it will 45 submerge. When the operator desires to rise to the surface of the water, he withdraws his arm from one of the sleeves 23 and opens valve 29 to release the compressed air from the storage tank 18 into the collapsible tank 25, thus causing the vessel to rise to the surface. It will be understood that, if desired, the compressed air motor 17 may be dispensed with and the single electric motor 13 provided for the propulsion of the vessel. 55 Suitable means is of course provided for the control of the motor which may be operated from the interior of the vessel, the occupant withdrawing his arms from the sleeves 23. It will be further understood 60 that the weight of the vessel is so distributed that it will maintain an even balance or keel in the water.

From the foregoing description taken in connection with the accompanying draw-

ings, the construction, manner of use and several advantages of the invention will be clearly and fully understood. The user first draws on the leg tubes or envelops 10 and the body of the vessel is then lifted and moved downwardly over the body of the occupant. The plate 9 is then tightly secured to the end of the body 5. The entire apparatus may be readily supported and carried by the occupant when walking or standing without serious inconvenience, the device being comparatively light in weight. The invention thus affords means which may be advantageously used in submarine explorations, the removal of mines, repairing ships, and also as a life saving device to permit steamer passengers to safely reach the shore when the steamer is sunk through collision or any other cause. It will also be appreciated that the apparatus is relatively simple in its construction and can therefore be produced at small manufacturing cost.

While I have herein shown and described the preferred construction and arrangement of the several parts employed, it is to be understood that the device is susceptible of considerable modifications therein and I, therefore, reserve the privilege of adopting all such legitimate changes as may be fairly embodied within the spirit and scope of the invention as claimed.

Of course it will be understood that the vessel may be provided with an oxygen supply tank so as to afford an ample supply of oxygen during a prolonged submergence of the vessel.

Having thus fully described my invention, what I claim is:—

1. A vessel of the character described including a body portion open at one end, a closure plate for the open end of said body, means to support the body of a person within said vessel, exterior means controllable by the occupant to submerge the vessel, flexible leg receiving envelops secured to said plate, and means for propelling the vessel through the water.

2. A vessel of the character described including a body portion open at one end and having means to support the body of a person within said vessel, a closure plate for the open end of said body, flexible leg receiving envelops secured to said plate, a collapsible tank secured to the under side of the vessel, means operable by the occupant to control the ingress and egress of water and air to and from the tank, and means for propelling the vessel through the water.

3. A vessel of the character described including a body having an entrance opening and a closure therefor, means within said vessel to support the body of an occupant, a collapsible tank secured to the under side of the vessel and controllable by the occupant

to submerge the vessel, a source of compressed air for said tank carried by the vessel, water inlet and air outlet valves in one end of the collapsible tank, a valve controlling the admission of compressed air to said tank, and means for propelling the vessel through the water.

In testimony whereof I hereunto affix my signature in the presence of two witnesses.

WORTH R. BARRINGER.
